nois

Application March 26, 1936, Serial No. 61,804

Term of patent 7 years

To all whom it may concern:

Be it known that we, George D. Wilkinson, a citizen of the United States, residing at Oak Park, in the county of Cook, State of Illinois, and Augustus F. Harter, a citizen of the United States, residing at 532 North Ridgeland Avenue, Oak Park, in the county of Cook, State of Illinois, have invented a new, original, and ornamental Design for a Range, of which the following is a specification, reference being had to the accompanying drawing, forming a part thereof, in which the figure of the drawing is a view in perspective of a range, showing our new design.

The undisclosed side of the range is like the side shown.

We claim:

The ornamental design for a range as shown and described.

GEORGE D. WILKINSON.
AUGUSTUS F. HARTER.
